UNITED STATES PATENT OFFICE.

EDWARD L. WATROUS, OF DES MOINES, IOWA, ASSIGNOR TO DAVID B. GANN, OF CHICAGO, ILLINOIS.

LEG-SOCKET.

1,211,797.

Specification of Letters Patent.

Patented Jan. 9, 1917.

Application filed April 18, 1910. Serial No. 556,279.

To all whom it may concern:

Be it known that I, EDWARD L. WATROUS, a citizen of the United States, residing at Des Moines, in the county of Polk and State 5 of Iowa, have invented a certain new and useful Leg-Socket, of which the following is a specification.

The object of my invention is to provide a leg socket especially adapted for use in connecting supporting legs with articles such, for instance, as washing machine bodies, which socket may be formed complete from a single piece of sheet metal and which is so arranged and constructed that it will not 10 only provide a socket for the leg but will also provide a gage by which a number of sockets may be connected to the body to be supported all at uniform distances from the lower edge of said body.

More specifically it is my object to provide 15 a socket of this class designed to be used in connection with and to coact with a round hoop at the lower portion of the body to be supported in such a manner that the socket 20 will accurately fit around the hoop and at the same time the hoop of itself will coact with the socket to firmly and securely hold a wooden leg driven into the socket.

My invention consists in certain details, 25 in the construction, arrangement and combination of the various parts of the device, whereby the objects contemplated are attained, as hereinafter more fully set forth, pointed out in my claims and illustrated in 30 the accompanying drawings, in which:

Figure 1 shows a front view of a socket embodying my invention. Fig. 2 shows a sectional view on the line 2-2 of Fig. 1. Fig. 3 shows a sectional view on the line 40 3-3 of Fig. 1, and Fig. 4 shows a vertical, central, sectional view of a socket embodying my invention applied to a part of a body to be supported and having a wooden leg in position therein.

Referring to the accompanying drawings, I have used the reference numeral 10 to indicate the front of the socket. The front is 45 preferably strengthened and reinforced by means of ribs 11 extended transversely and

it is also provided with an opening 12 near 50 its center to receive a screw. The sides of the socket are indicated by the numeral 13 and preferably flare outwardly away from each other toward the rear of the socket. These sides are provided at their edges with 55 the flanges 14, which flanges have at their upper and lower ends the screw openings 15. The said sides are provided with reinforcing ribs 16 in line with the ribs 11 and being a continuation of said ribs 11. The 60 top of the socket is indicated by the numeral 17 and it has an upwardly extended flange 18 provided with a screw opening 19.

As will be seen by referring to Figs. 2 and 3 of the drawings, the rear of the socket is 65 of substantially segmental shape to fit the contour of a round washing machine body or the like. The sides of the socket extend a considerable distance below the front, and an integral cross-piece 20 extends across 70 the throat of the socket between said sides below the front wall 10 and thus forms a yielding bearing for the tub leg. The socket flares outwardly below the front 10. The cross-piece 20 is formed and positioned by 75 folding inward the lower portions of the side walls 13 approximately midway of their height to form walls 21 substantially perpendicular to the plane of the front but which do not extend inward to the bases of 80 the side walls. This cross piece 20 is provided at its upper edge with outwardly extended sharpened points 22 which are designed to engage a wooden leg driven into the socket. At the bottom of the cross piece 85 20 is an extension 23 projected rearwardly and designed to extend under the lower edge of the body of a washing machine or the like indicated in Fig. 4 by the numeral 24. The cross piece 20 and the extension 23 are provided with a number of strengthening and reinforcing ribs 23a. This body is provided with a round hoop 25 of the ordinary construction. The part 23 is provided with means by which it may be secured to the 90 bottom of the body 24 such, for instance, as an opening therein to receive a screw as shown at 26 in Fig. 4.

One of the important features of my present invention is that the flanges 14 and the sides 13 are provided at a point between the front 10 and the cross piece 20 with a 5 rounded rib 27 and in this connection another important feature is that the sheet metal cross piece 20 is arranged a short distance in front of the adjacent portions of the flanges 14 so that the cross piece 20 is 10 substantially in line vertically with the concave portion of the rounded rib 27. The advantage of this part of my invention is that, when the socket is placed on an article to be supported that is provided with a 15 round hoop 25, the said hoop will be received in the rounded rib 27 so that the flange 14 may fit tightly against the article to be supported and the advantage of having the sides 13 tapered from a maximum width at 20 their lower ends to a minimum at their upper ends, as shown in Fig. 4, is that when a wooden leg 28 is placed in the socket the front of the leg will fit flat against the front 10 and the rear of the leg will fit against the body 24 at its top and against the 25 rounded hoop 25 and the cross piece 20 at its rear so that the leg will stand in a position slightly inclined away from the adjacent side of the body to which it is supported. 30 In devices of this class that are used in connection with a washing machine body or the like having a round hoop, it is essential to have the upper end of the socket of less depth than the lower end in order to permit 35 a leg to be inserted therein outside of the hoop and to have the socket fit against the leg at its top and also at the point adjacent to the rounded hoop as said rounded hoop necessarily extends outwardly from the 40 washing machine body.

In practical use it is obvious that the entire socket may readily and easily be formed of a single piece of sheet metal by means of suitable dies and formers. It is 45 also obvious that in attaching said sockets to a washing machine body or the like the operator may very quickly and accurately place them in position because of the fact that there is a double gage for each socket. 50 The extension 23 is placed under the edge of the washing machine body and the rounded rib 27 is placed over the round hoop. Therefore it is very easy to position the sockets upon the washing machine body all in the 55 same plane so that when legs of the same size are used the washing machine or the like will be supported in a level horizontal position. The sockets are secured to the body by means of screws or other fastening 60 devices in the ordinary way and after each socket is firmly fixed to the washing machine body or the like the operator drives the wooden legs 28 into the sockets until the

upper ends of the legs reach the top of the socket. In driving these wooden legs into 65 the sockets they will be firmly wedged between the round hoops 25 and the front of the socket. In addition to this the legs will be held in position in the sockets by means of the pointed projections 22 so that when 70 the legs are once driven in position they will be firmly and securely held without additional securing devices although I have provided an opening 12 in the front of the socket to receive a screw by which the leg 75 may be additionally secured in position.

I claim as my invention:

1. A leg socket integral throughout and composed of sheet metal and adapted to be attached to a tub, said socket being of uniform width from top to bottom but tapering upwardly in thickness, said socket having a bar across its throat and forming the inner wall thereof and being adapted to yield to expand the throat when the socket is attached to a tub.

2. A leg socket consisting of a single piece of sheet metal, said socket adapted for attachment to a tub or other support and being of tapering thickness from bottom to top and having an integral sheet metal cross-piece which forms a yielding inner wall for the mouth of said socket and is provided with integral spurs arranged for engagement with the wooden leg carried by 95 the socket.

3. A device of the class described formed complete of a single piece of sheet metal and comprising a front and sides, and means for attaching the same to a support, said sides 100 being of tapering width from bottom to top and being extended below said front, and a yielding cross-piece integral with said sides and located adjacent their lower ends and spaced apart from their inner edges, said 105 cross-piece having ribs therein extending crosswise thereof.

4. A leg socket of sheet metal comprising a hollow body portion having a front member and side members, said side members being tapering in width, apertured flanges extending laterally from said side members, a cross-piece below said front member and formed integral with the side members and protruding at the throat of said socket so 11 that a leg of substantially uniform thickness may be placed in the socket with its front in engagement with the socket front and its rear in engagement with said cross-piece, said cross-piece being spaced apart from the 120 article to which the socket is applied by a distance sufficient to admit a tub hoop under the leg near said cross-piece.

5. An improved leg socket adapted to be attached to a tub, comprising a main body 125 portion having a front of rectangular out-

line, side members integral with the front and projecting below the same, a sheet metal cross-piece connected with said side members below said front and so positioned as

- 5 to be spaced apart from a tub on which the socket may be carried, and an extension at the lower edge of said cross-piece arranged

to project under the edge of the supporting tub.

Des Moines, Iowa, March 16, 1910.

EDWARD L. WATROUS.
